UNITED STATES PATENT OFFICE

161,265

CASING FOR TOASTER

Ivar Jepson, Oak Park, Ill., assignor to Sunbeam Corporation, Chicago, Ill., a corporation of Illinois

Application March 24, 1950, Serial No. 8,733

Term of patent 14 years

(Cl. D81—10)

To all whom it may concern:

Be it known that I, Ivar Jepson, residing at Oak Park, in the county of Cook and State of Illinois, have invented a new, original, and ornamental Design for a Casing for Toaster, of which the following is a specification, reference being had to the accompanying drawing, forming part thereof.

In the drawing:

Figure 1 is a top plan view of the toaster embodying my new design;

Figure 2 is a side elevation; and

Figure 3 is an end elevation thereof.

I claim:

The ornamental design for a casing for toaster, substantially as shown.

IVAR JEPSON.
